(57) **CLAIM**

The ornamental design for an athletic shorts, as shown and described.

DESCRIPTION

FIG. 1 is a top plan view of athletic shorts, showing my new design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a bottom plan view thereof.

The dot-dot-dash broken lines depicting the human shown in the drawings are for environmental purposes only and form no part of the claimed design.

The dashed broken lines shown on the article shown in the drawing views represents a stitching line.
